US0D1083116S

(12) **United States Design Patent** (10) **Patent No.:** **US D1,083,116 S**
(45) **Date of Patent:** **** Jul. 8, 2025**

(54) **WOUND DRESSING**

(71) Applicant: **Mölnlycke Health Care AB**,
Gothenburg (SE)

(72) Inventors: **Maria Gustin Bergström**, Linköping (SE); **Karin Östan**, Nödinge (SE); **Angelica Andresen**, Kungsbacka (SE); **Linda Östlund**, Kungsbacka (SE); **Sandra Tillman**, Gothenburg (SE); **Anita Haraldsson-Hedbratt**, Mölnlycke (SE); **Lena Jacobsson**, Gothenburg (SE); **Patrick Rodzewicz**, Gothenburg (SE); **Sofia Hermansson**, VÄstra Frölunda (SE)

(73) Assignee: **Mölnlycke Health Care AB**, Mölndal (SE)

(**) Term: **15 Years**

(21) Appl. No.: **29/868,394**

(22) Filed: **Dec. 1, 2022**

CLAIM

The ornamental design for a wound dressing as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front plan view of a first embodiment of a wound dressing showing our new design;

FIG. 2 is a top plan view thereof;

FIG. 3 is a left side elevational view thereof;

FIG. 4 is a rear elevational view thereof;

FIG. 5 is a bottom plan view thereof;

FIG. 6 is a right side elevational view thereof;

FIG. 7 is a front plan view of a second embodiment of a wound dressing showing our new design;

FIG. 8 is a top plan view thereof;

FIG. 9 is a left side elevational view thereof;

FIG. 10 is a rear elevational view thereof;

FIG. 11 is a bottom plan view thereof;

FIG. 12 is a right side elevational view thereof;

FIG. 13 is a front plan view of a third embodiment of a wound dressing showing our new design;

FIG. 14 is a top plan view thereof;

FIG. 15 is a left side elevational view thereof;

FIG. 16 is a rear elevational view thereof;

FIG. 17 is a bottom plan view thereof;

FIG. 18 is a right side elevational view thereof;

FIG. 19 is a front plan view of a fourth embodiment of a wound dressing showing our new design;

FIG. 20 is a top plan view thereof;

FIG. 21 is a left side elevational view thereof;

FIG. 22 is a rear elevational view thereof;

FIG. 23 is a bottom plan view thereof; and,

FIG. 24 is a right side elevational view thereof.
